CLAIM

The ornamental design for a product dispenser with animated LED illumination, as shown and described.

DESCRIPTION

FIG. 1 is a front view of a first LED illumination in an animated sequence for the product dispenser with animated LED illumination;

FIG. 2 is a front view of a second LED illumination thereof; FIG. 3 is a front view of a third LED illumination thereof; FIG. 4 is another front view of the first LED illumination thereof;

FIG. 5 is another front view of the second LED illumination thereof; and,

FIG. 6 is another front view of the third LED illumination thereof.

The broken lines are illustrative of the product dispenser and form no part of the claimed design.

The LED illumination animation is shown separately from the article of manufacture in FIGS. 1-3 for ease of visibility.

1 Claim, 6 Drawing Sheets
